DISPENSING CONTAINER FOR GRANULAR MATERIALS WITH BUILT-IN MEASURING TRAP

Walter J. Sprucinski, Torrington, Conn.

Application May 27, 1950, Serial No. 164,695

4 Claims. (Cl. 222—456)

1

This invention relates to dispensers and more particularly to a container which is provided with adjustable means for automatically measuring predetermined amounts of material to be poured from the container, and which is adapted for use with granular, powdered, or flake soap or other fluent materials.

One object of this invention is to provide a device of the above nature in which the amount of material to be measured will be determined by the relationship of an adjustable baffle to a concave trough in the container.

Another object is to provide a device of the above nature in which the baffle may be adjustably held in different positions by an interlocking relationship with the container cover.

A further object is to provide a device of the above nature which will be simple in construction, inexpensive to manufacture, easy to use and manipulate, adapted to protect and conserve its contents, ornamental in appearance, and very efficient and durable in use.

With these and other objects in view, there has been illustrated on the accompanying drawing one form in which the invention may conveniently be embodied in practice.

In the drawing:

Fig. 1 is a perspective view showing the improved dispensing container with parts broken away to show the interior construction.

Fig. 2 is a plan view of the same.

Fig. 3 is a side view showing the container tipped up as it would appear in use for dispensing powder.

Fig. 4 is a side view of the same showing the baffle in a different adjusted position from that of Fig. 1.

Fig. 5 is an edge view of the same.

Referring now to the drawing, in which like reference numerals denote corresponding parts throughout the several views, the numeral 10 indicates a rectangular container which comprises side walls 11, 12, end walls 13, 14, and a bottom wall 15, said walls preferably being of a transparent plastic material and secured together by cement or welding.

The interior of the container 10 is divided by a vertical rectangular partition baffle 16 which is slidably supported in vertical grooves 17, 18 formed in the inner surfaces of the side walls 11, 12, thus providing a main storage compartment 19 and a relatively narrow discharge chute 20 adjacent the end wall 13.

In order to control the amounts of material which will pass from the storage compartment 19

2

under the lower end of the baffle 16, and into the discharge chute 20, provision is made of a trough 21 which is concave upwardly and extends between the side walls 11, 12. The trough 21 is secured to the side walls 11, 12, and to the end wall 13 and bottom wall 15 in a nearly concentric relationship to the lower edge of the baffle 16, this relationship being variable however, because of the adjustability of said baffle.

When the container 10 is in erect position, as shown in Fig. 4 for example, it will be seen that fluent material M in the storage compartment 19 will flow by gravity into the concave trough 21 in varying amounts depending upon the adjustment of the baffle 16. If the container 10 should then be tilted forwardly as illustrated in Fig. 3, it will be seen that a predetermined amount of the fluent material in the trough 21 will flow out through the discharge chute 20, while the remainder of the material M will be dropped downwardly and be retained behind the baffle 16.

In order to prevent the material M in the compartment 19 from escaping from the container 10 when said container is tilted, and also to exclude dust from said material at all times provision is made of a flat cover 22 which is slidable in a pair of horizontal grooves 23, 24 formed in the inner surfaces of the side walls 11, 12 adjacent the top thereof. The inner end of the cover 22 is adapted to enter selectively into either of a pair of horizontal grooves 25, 26 formed in the baffle 16, thus providing a means whereby said baffle may be locked selectively in two different positions for controlling the amount of material M which will enter the trough 21 at each depressing operation.

The adjustment of the cover 22 and the removal thereof to permit the compartment 19 to be refilled, is facilitated by providing a recessed outer end portion or thumbpiece 27 which projects outwardly beyond the end wall 14, said end wall being somewhat shortened at its upper end and being slidably engaged by the cover 22.

Operation

In use, a supply of granulated soap or other fluent material to be dispensed will first be placed in the storage compartment 19, this operation being permitted by the sliding of the cover 22 outwardly. After the material M has been placed in the compartment 19, the cover 22 will be closed so that its inner end will enter one of the grooves 25, 26 in the baffle 16, thus locking said baffle in the desired vertically adjusted position.

This arrangement will, of course, permit a quantity of the material M to flow beneath the baffle 16 into the trough 21 by gravity, so that a predetermined quantity of said material may be poured from the container through the discharge chute 20 when said container is tipped, as shown in Fig. 3, at each dispensing operation.

When the container 10 is restored to upright position, as shown in Fig. 1, more of the material M will flow beneath the baffle 16 so that the chute 20 will again contain the predetermined quantity of the material.

It will be understood that vertical adjustment of the baffle 16 will regulate the amount of material which flows through the trough 21 into the chute 20 and that said baffle may be released for a different adjustment at any time, merely by disengaging the cover 22 from the groove 25 or 26.

While there has been disclosed in this specification one form in which the invention may be embodied, it is to be understood that this form is shown for the purpose of illustration only and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a dispensing container having side, end, and bottom walls, a longitudinally slideable partition baffle mounted between said side walls and dividing the interior of said container into a storage compartment and a discharge chute, said baffle having a lower edge spaced from an inner portion of said container for regulating the passage of fluent material from said storage compartment to said discharge chute, a cover for said storage compartment, said cover being slid-

ably mounted between said side walls for movement toward and away from said baffle, and means engageable by said cover for locking said baffle against vertical sliding movement.

5. The invention as defined in claim 1 in which said locking means comprises a groove in the upper part of said baffle adapted to receive the end portion of said cover.

3. The invention as defined in claim 1, in which said locking means comprises a plurality of grooves in the upper part of said baffle, said grooves being selectively engageable by the end of said cover for holding said baffle in different elevated positions.

4. In a dispensing container having side, end, and bottom walls, a partition baffle mounted between said side walls and dividing the interior of said container into a storage compartment and a discharge chute, an upwardly concave trough secured in the bottom of said container, said baffle having a lower edge located above the bottom of said trough and between the edges thereof, whereby the passage of fluent material from said storage compartment to said discharge chute may be accurately controlled, means mounting said baffle for vertical sliding movement, whereby the distance between the lower edge of said baffle and the bottom of said trough may be varied, and a cover slidably mounted between said side walls for closing said storage compartment, said baffle having means selectively engageable by said cover for locking said baffle in different positions.

WALTER J. SPRUCINSKI.
